UNITED STATES PATENT OFFICE.

DANIEL O. WARD, OF OAK PARK, ILLINOIS; NELLIE LEE WARD ADMINISTRATRIX OF
SAID DANIEL O. WARD, DECEASED.

BLANK FOR SELF-LOCKING NUTS.

1,101,501.

Specification of Letters Patent. Patented June 23, 1914.

Original application filed April 15, 1912, Serial No. 690,780. Divided and this application filed March 3, 1913. Serial No. 751,856.

To all whom it may concern:

Be it known that I, DANIEL O. WARD, a citizen of the United States, residing at Oak Park, in the county of Cook and State of Illinois, have invented certain new and useful Improvements in Blanks for Self-Locking Nuts, of which the following is a specification, reference being had therein to the accompanying drawing.

10 This invention relates to improvements in blanks for self-locking nuts, and has for its object the provision of a device of this character which may be readily and cheaply made and which may, in a single pressing operation, be converted into an effective self-locking nut.

The characteristic of my improved blank is the fact that the use of special implements, during the pressing operation, to 20 keep the threaded opening or aperture of the nut clear, so as not to impair the capability of the nut to receive a bolt entirely therethrough, is obviated.

The details in the construction and arrangement of my improved blank will be apparent from the specific description hereinafter contained when read in connection with the accompanying drawings forming a part hereof, and wherein the preferred embodiment of the invention is illustrated.

In the drawings:—Figure 1 is a side elevation of the blank; Fig. 2 is a cross section of the blank before it is threaded, and Fig. 3 is a similar view of the threaded blank 35 complete adapted to be pressed to produce the self-locking nut illustrated in section, Fig. 4, and top plan, Fig. 5, this completed nut constituting the subject matter of my co-pending application, Serial No. 690,780, filed April 15, 1912, of which the present application is a division.

Referring more particularly to the drawings, wherein like reference characters designate corresponding parts in the several views, A represents the body of the blank formed of metal and of suitable contour provided with a bore or central opening B, and a reduced, preferably annular portion C projecting from one face of the body to constitute what I may properly term a boss, the boss being provided with an outwardly flaring inner surface D converging inwardly to the bore B, said bore not only passing through the body A but also partially

through the annular projection C so that a 55 continuous passage is provided through the nut. The bore B is threaded to constitute the usual helical convolutions adapted to engage a similarly threaded bolt, and the base of the nut is recessed as at E to prevent damage to the lower threads of the blank under the compressing strains to which I will now allude.

In completing the self-locking nut from my blank as above defined, pressure is applied to the outer surface of the boss C to cause the metal to be compressed and flow axially and radially of the nut, resulting in the pressing of the adjacent upper convolutions of the interiorly threaded body closer 70 together than the distance between the convolutions of the remaining threaded portion in the lower part of the body, resulting, when the nut is applied to a bolt, in a strong binding action between the nut and bolt by 75 reason of the varying distances between the convolutions as compared to the uniformly separated convolutions on the bolt.

Heretofore when pressure has been applied to the outer surface of an enlargement 80 or boss on a nut of the general character here in question, a mandrel or stem has been placed on the interior of the nut prior to the pressing operation to prevent the flowing of the metal into the open portion or above the 85 open portion of the nut, thus obstructing the passage therethrough, but this is obviated in my blank by reason of the fact that the boss, while arranged directly above the threaded interior of the nut, is formed to uniformly 90 recede outwardly and away from the threads or bore in the body, so that the inward or radial flowing of the metal under the compression of the boss simply fills the space normally within the tapering inside of the 95 boss and not in or over the central apertured portion of the nut.

The operation has other advantages so far as effects the completed nut, as reducing the depth of the outer or terminal portion 100 of the thread so that where the thread is finest it is of less depth than the relative depth of the inner convolutions of the thread, thus giving the terminal or end of the thread sufficient strength to resist any 105 stripping tendency in the application of the nut to a bolt. The terminal or end of the thread also, as a result of the compression

and the inclined inner side of the boss gradually merges to nothing into the boss (as represented at X) through the major part of the upper convolution correspondingly receding outwardly from the normal bore of the nut, so that the bolt cannot engage the said convolution until it reaches a substantially deepened and strengthened part thereof.

10 While I have herein disclosed a blank constituting a special embodiment of my invention, it will be apparent to persons skilled in the art that the invention is capable of embodiment in other forms and devices as 15 may be in keeping with the hereto appended claims.

I claim:—

1. A blank for self locking nuts comprising a metal base portion having a threaded bolt aperture, and a boss projecting outwardly from the central portion of said base portion, the boss being of substantially less width than the major portion of the base and adapted to be displaced independently of the latter, the aperture in the base registering with an outwardly flaring opening formed by inclining the inner surface of the boss from the end thereof inwardly to the wall of the aperture, substantially as described.

2. A blank for self locking nuts comprising a base portion having a threaded bolt aperture and a boss projecting outwardly from the central portion of said base portion, the boss being of substantially less width than the major portion of the base and adapted to be displaced independently of the latter, said boss being formed on its inner surface to recede to a substantial extent away from the thread in the wall of the aperture to the end of the blank, and said aperture registering with the opening on the interior of the boss.

3. A blank for self locking nuts comprising a base portion having a threaded bolt aperture, and a projection adjoining said aperture and extending outwardly from the central portion of the base portion, the boss being of substantially less width than the major portion of the base and adapted to be displaced independently of the latter, said projection having its inner face formed to recede to a substantial extent away from the thread in the wall of the aperture to the end of the blank, substantially as described.

4. A blank for self locking nuts comprising a base portion having a bolt aperture and a boss projecting outwardly from the central portion of the base portion, the boss being of substantially less width than the major portion of the base and adapted to be displaced independently of the latter, the aperture in the base portion registering with an outwardly flaring opening formed by inclining the inner surface of the boss from

the end thereof inwardly to the wall of the aperture, the blank being interiorly threaded through the bolt aperture but not through that portion of the boss adjoining the relatively enlarged space constituted thereby. 70

5. A blank for self locking nuts comprising a base portion having a bolt aperture and a boss projecting outwardly from the central portion of the base portion, the boss being of substantially less width than the major portion of the base and adapted to be displaced independently of the latter, said boss being formed on its inner surface to recede to a substantial extent away from the wall of the aperture to the end of the blank 80 and said aperture registering with the opening on the interior of the base, the blank being interiorly threaded through the bolt aperture but not through that portion of the the boss adjoining the relatively enlarged 85 space constituted thereby and which recedes away from the thread.

6. A blank for self locking nuts comprising a base portion having a bolt aperture and a projection adjoining said aperture extending outwardly from the central portion of the base portion, the boss being of substantially less width than the major portion of the base and adapted to be displaced independently of the latter, said projection having its inner face formed to recede a substantial extent away from the wall of the aperture to the end of the blank, the blank being inwardly threaded from the bolt aperture but not through that portion of the projection adjoining the relatively enlarged space constituted thereby and which recedes away from the thread.

7. A blank for self locking nuts comprising a base portion having a bolt aperture and a projection adjoining said aperture and extending outwardly from the central portion of the base portion, the boss being of substantially less width than the major portion of the base and adapted to be displaced independently of the latter, said projection having a broad inner portion adjoining the bolt aperture and an outer portion receded a substantial extent away from the wall of the aperture, the blank being interiorly threaded through the bolt aperture but not through that portion of the projection adjoining the relatively enlarged space constituted thereby and which recedes away from the thread so that the projection when compressed will affect the threads in the base therebelow but will not flow into the aperture. 110

8. A blank for self locking nuts comprising a threaded base portion having a bolt aperture, and a boss adjoining said aperture projecting outwardly from the central portion of the base portion, the boss being of substantially less width than the major portion of the base and adapted to be displaced 125

independently of the latter, said boss being formed on its inner surface to recede gradually from the terminal of the thread to a substantial distance laterally away from the 5 wall of the aperture, said aperture registering with the opening on the interior of the base, the blank being interiorly threaded through the bolt aperture but not through

that portion of the boss adjoining the enlarged space constituted thereby. 10

In testimony whereof I affix my signature in presence of two witnesses.

DANIEL O. WARD.
